UNITED STATES PATENT OFFICE.

AUGUST E. NEFF, OF CHICAGO, ILLINOIS, ASSIGNOR TO PHOENIX TRIMMING COMPANY, OF CHICAGO, ILLINOIS, A CORPORATION OF ILLINOIS.

DESIGN FOR AN ORNAMENTAL FRINGE.

Application filed May 8, 1922. Serial No. 2,124. Term of patent 3½ years.

To all whom it may concern:

Be it known that I, AUGUST E. NEFF, a citizen of the United States, residing at Chicago, in the county of Cook and State of Illinois, have invented a certain new, original, and ornamental Design for Ornamental Fringe, of which the following is a specification, reference being had to the accompanying drawing, forming a part thereof.

The drawing shows an elevation view of the ornamental fringe showing my new design thereof.

I claim:

The ornamental design for ornamental fringe as shown.

AUGUST E. NEFF.
